UNITED STATES PATENT OFFICE

94,092

DESIGN FOR AN AIRPLANE WING STRUCTURE MODEL

Raymond N. Massie, Chicago, Ill.

Application May 12, 1934, Serial No. 51,756

Term of patent 14 years

To all whom it may concern:

Be it known that I, Raymond N. Massie, a citizen of the United States, and residing in the city of Chicago, in the county of Cook and State of Illinois, have invented a new, original, and ornamental Design for an Airplane Wing Structure Model, of which the following is the specification, reference being had to the accompanying drawing, forming a part thereof.

On the drawing:

Figure 1 is a top plan view of an airplane wing structure model showing my new design, and fur-

thermore showing other parts of the airplane in dotted lines.

Figure 2 is a side elevation of the airplane wing structure model, including a dotted line showing of other parts of the airplane.

Figure 3 is a rear end view of the airplane wing structure model, showing other parts of the airplane in dotted lines.

I claim:

The ornamental design for an airplane wing structure model as shown in full lines.

RAYMOND N. MASSIE.
